UNITED STATES PATENT OFFICE.

JOHN B. DOBSON, OF PHILADELPHIA, PENNSYLVANIA.

DRYING-MACHINE.

SPECIFICATION forming part of Letters Patent No. 513,896, dated January 30, 1894.

Application filed August 24, 1893. Serial No. 483,968. (No model.)

To all whom it may concern:

Be it known that I, JOHN B. DOBSON, a citizen of the United States, residing in Philadelphia, Pennsylvania, have invented certain 5 Improvements in Drying-Machines, of which the following is a specification.

The object of my invention is to remove the water of condensation from the interior of all the drying cylinders used for drying paper, 10 cloth, &c., without causing back pressure in the steam pipes, and without wasting the steam to any great extent. This object I attain in the following manner, reference being had to the accompanying drawings, in which—

15 Figure 1, is a side view illustrating my improved draining system, the bearings and frames of the machine being removed to avoid confusion. Fig. 2, is a sectional view of a portion of a drying cylinder and the pipes, the 20 section being on the line 1—2, Fig. 1.

25 A are the drying cylinders arranged generally in series as shown, and around which the paper or cloth is passed. The cylinders A are hollow, and the shell is made as thin as possible, so that the steam within the cylinder will readily dry the paper or cloth. Water 30 of condensation, however, quickly accumulates in these cylinders, and if this water is not removed regularly, it will accumulate and 35 tend to cool the cylinders and cause them to sweat, and in many cases mark the paper, but by my invention the water of condensation is removed regularly from each cylinder.

40 B is the steam inlet pipe communicating with a live steam pipe B' extending, preferably, the full length of the machine. This live steam pipe B' is connected to the steam inlet a of each cylinder by pipe b, clearly shown in Fig. 2, so that the live steam will readily flow into the cylinders.

45 Running parallel with the live steam pipe B' is the water discharge pipe D. This pipe is connected with the live steam pipe at one end by an equalizing pipe e and is connected to a trap E at the opposite end by a pipe e'; an equalizing pipe e² connects the live steam pipe B' also to the trap. This trap has an ordinary valve f and is connected to a discharge pipe F which carries off the water of 50 condensation. The steam pipe B' being connected at both ends to the drainage pipe, water of condensation cannot back up in said

steam pipe and prevent the steam entering the cylinders as is the case in the majority of paper drying machines as now constructed. 55 The equalizing pipe e drains the steam pipe B so that only dry steam will be admitted to the cylinders. The valve f of the trap E is controlled by a float f' which lifts the valve when the water of condensation in the device 60 reaches a certain level.

Extending up from the pipe D is a series of outlet pipes d which pass into the cylinder through the stuffing box a in the head of the cylinder, and each pipe d has an extension d' 65 terminating at a point near the bottom of the cylinder, forming the short leg of a siphon, the pipe d forming the long leg. The pipe d may be enlarged at d² as shown by dotted lines in Fig. 2 to increase the steam space between the water level in the pipe d and the cylinder, so that when the water in the cylinder closes the mouth of the pipe d' the quantity of steam in the pipe d will condense, forming a partial vacuum and water in the cylinder will be drawn through the short leg of 70 the siphon until the water level in the cylinder is below the mouth of the pipe breaking the siphon. Thus it will be seen that the exhaust pipe of each cylinder acts independently, as there is practically no connection between the vacuum spaces of the exhaust pipes. The water level in the several pipes will be raised by the admission of water from the 75 several cylinders, and when it reaches a certain level the valve of the trap will open, and the water will flow out through the pipe F. The valve will close when the water reaches a certain low level, and the operation 80 will be repeated. Thus it will be seen that high pressure steam is not required for the cylinders, as I do not rely upon the action of the live steam to force the water out of the cylinders, but rely on the condensation of steam in the exhaust pipe to start the siphon. 85

I claim as my invention—

1. The combination of the drying cylinder, the steam inlet, and the discharge pipe for the water of condensation, said discharge pipe extending near to the bottom of the cylinder, 100 and having its outer end water sealed, so that when the water in the cylinder closes the mouth of said pipe the steam in the pipe will be condensed, forming a partial vacuum, which

will start the siphon discharge, substantially as described.

2. The combination of the drying cylinders of a drying machine, the inlet steam pipe, the 5 outlet pipe for the water of condensation, said pipes being connected together, and to a steam trap, steam inlet pipes extending from the said steam pipe to the cylinder, and water exhaust pipes extending from each cylinder to 10 the outlet pipe, the whole being constructed so that water will remain at a certain level in each exhaust pipe, substantially as described.

3. The combination of the drying cylinders, an inlet pipe *b* and an exhaust pipe *d* for 15 each cylinder, a steam pipe *B'* coupled to said steam inlet pipe, and a water outlet pipe *D* coupled to each exhaust pipe, said steam pipe *B'* and water outlet pipe *D* being connected together at each end, a trap connected to said 20 pipes, to form a water level in each exhaust pipe, so that when the water accumulates in any one of the cylinders, it will trap the steam in the exhaust pipe, substantially as specified.

4. The combination of the steam inlet pipe, 25 the water discharge pipe coupled together and to a trap so as to equalize the pressure, dry-

ing cylinders, steam inlet pipe extending from the steam pipe to the drying cylinder, exhaust pipes for the water of condensation, extending from the cylinders to the water pipe, said 30 exhaust pipe being enlarged above the water level so as to form an increased steam space, substantially as described.

5. The combination of the steam inlet pipe, the exhaust pipe for the water of condensation, said exhaust pipe being below the steam inlet pipe, a drying cylinder, a pipe extending from the steam inlet pipe to the drying cylinder and a pipe extending from the cylinder to the exhaust pipe, with a coupling 35 40 pipe extending from the steam inlet pipe down to the exhaust pipe so that the steam inlet pipe is free from water of condensation, substantially as described.

In testimony whereof I have signed my 45 name to this specification in the presence of two subscribing witnesses.

JOHN B. DOBSON.
